UNITED STATES PATENT OFFICE.

GEORGE W. CLARK, OF CHICAGO, ILLINOIS.

COMBINED COAL AND GAS RANGE.

1,191,668.

Specification of Letters Patent. Patented July 18, 1916.

Application filed February 12, 1914. Serial No. 818,202.

To all whom it may concern:

Be it known that I, GEORGE W. CLARK, a citizen of the United States, residing at Chicago, county of Cook, State of Illinois, have invented a certain new and useful Improvement in Combined Coal and Gas Ranges, and declare the following to be a full, clear, and exact description of the same, such as will enable others skilled in the art to which it pertains to make and use the same, reference being had to the accompanying drawings, which form a part of this specification.

The present invention has for its object to produce simple attachments to an ordinary coal stove or range by means of which it is possible to cook, broil or bake with gas as the fuel without interfering in any way with the ordinary use of the stove or range when coal is used as the fuel.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a front view of a range equipped in accordance with the present invention and ready for use as a gas range; Fig. 2 is a section taken approximately on line 2—2 of Fig. 1, but on a somewhat larger scale than Fig. 1; Fig. 3 is a section taken approximately on line 3—3 of Fig. 2; and Fig. 4 is a section taken approximately on line 4—4 of Fig. 3.

In accordance with one feature of my invention, by means of which it is possible to cook with gas upon the top of the range, I form on the side of the range, 1, opposite that at which the fire pot is located, an extension, 2, supported from below by a suitable bracket or brackets, 3; this extension being provided with any desired number of cooking holes containing burners, (not shown) to which gas is supplied through a pipe, 4, lying along the front of the extension and provided with suitable valves, 5. In the front bracket, 3, is a suitable shallow drawer or tray, 6. This arrangement makes the gas holes independent of the holes intended to receive utensils adapted to be heated from the coal fire; permits both coal and gas to be used simultaneously or either to be used alone; and at the same

time adds only slightly to the width of the range.

The principal feature of my invention, however, has to do with the heating of the oven so that gas may be used for baking.

The present types of ranges are the result of long years of experiment and use and it is therefore very desirable that the construction of the oven and the heating flues or draft passages associated with the same be altered as little as possible in order not to lose in efficiency and effectiveness when the oven is heated from a coal fire. In accordance with my invention, the oven and the draft passages or heating passages associated therewith are left unchanged, the gas appliances being simply attachments which are placed within the usual oven when the latter is to be heated with gas and are removed from the oven and leave it the same as any other oven in a coal stove or range when the heating is by means of a coal fire.

Referring to the drawings, 7 represents the oven and 8 the usual oven door provided at the bottom with hinges, 9. In accordance with my invention, I place on the front of the range, just below the oven door, a gas supply pipe, 10, terminating at about the middle of the door.

11 is a suitable burner adapted to be laid upon the floor of the oven and provided with a neck or extension, 12, which is adapted to project through the oven opening and engage with the end of the supply pipe 10; the end of the supply pipe 10 and the adjacent end of the extension or neck, 12, being so shaped that when the two are simply brought in contact with each other they produce a sufficiently tight joint to prevent the escape of gas. In order to permit the neck or extension 12 to project out of the front of the oven, I cut in the bottom of the oven door an opening, 13, which is controlled by a small auxiliary door, 14, hinged within the main door, (which is illustrated as being hollow, as is customary). The auxiliary door is hinged to the main door at a point above the opening 13, as indicated at 15 so that when the oven door is closed the auxiliary door tends to swing down by gravity and close the opening 13. When the oven door is swung open, the auxiliary door swings on its hinge and uncovers the opening 13 so that whenever the oven door is open, the burner may be slipped

into the oven and its neck or extension passed through the opening 13 in the oven door without paying any attention to the auxiliary door. When the oven door is 5 closed, after the insertion of the burner, the auxiliary door rides up upon the extension 12, so that there is no interference with the closing of the oven door.

It is necessary to supply considerable free 10 air to the gas burner, in order to support combustion properly, and therefore I make the opening 13 in the oven door larger than the cross sectional area of the extension 12 in order to permit air to flow into the oven 15 when the burner is in place. It is of course not desirable that the cold air be allowed to flow freely into any part of the oven because its only purpose is to supply the oxygen necessary for combustion and therefore 20 I provide the burner with wings, 16, projecting laterally and downwardly therefrom throughout substantially its entire length; the burner with its wings forming an inverted trough extending along the bottom of 25 the oven and confining the air entering the opening 13 so that the only outlet for the latter after entering the opening in the oven door is through suitable openings provided in the burner device whereby the air is permitted 30 to enter the combustion zone. The burner itself may take various forms, but I have obtained very satisfactory results from a burner made in the form of an elongated narrow 0. This is in effect a long double 35 burner having between the two members thereof a long narrow passage which constitutes the outlet for the incoming air and compels this air to enter the combustion zone.

40 Since the heat of the burner flame is concentrated in a comparatively narrow zone, I prefer to place over the burner a suitable flame spreader, 17, which is somewhat smaller than the corresponding transverse 45 dimensions of the oven so as to permit the gaseous products of combustion to flow underneath the same and up past its edges; the flame spreader forming the effective bottom of the oven when heated with gas. The 50 flame spreader may be supported on suitable ledges or rests, 18, at the sides of the oven or it may be connected to the burner in such a way as to make the burner and the spreader a single attachment to be placed in 55 the oven. In the arrangement shown, there are several arms, 19, extending upwardly from the outer edges of the burner wings 16 and secured to the flame spreader. These arms do not interfere with the free flow of 60 the gaseous combustion products from the burner and at the same time connect the burner and the spreader together so that they may be placed in the oven and removed therefrom as a single piece.

65 It is desirable that the combustion gases

be allowed to escape from the oven when the latter is being heated by means of the burner, without permitting the combustion gases to enter the room in which the range is located. I have therefore provided a discharge outlet leading from the oven to the main flue 21, the outlet being controlled by a suitable damper which is kept closed when the oven is heated by means of the coal fire and is opened while gas is being burned in 70 the oven. Thus the heat is prevented from escaping from the oven when coal is used, while the objectionable combustion gases are permitted to escape out of the chimney when gas is burned. In the arrangement 75 illustrated, I have arranged in the upper rear corner of the oven a discharge outlet, 22, by means of which the oven and the smoke flue are placed in communication with each other. Controlling this outlet is a hinged 80 damper, 23, which tends always to swing down under the action of gravity and close the outlet. On the rear wall of the oven, preferably in a vertical groove or depression, 85 24, formed in the wall, is a vertically slid- 90 able rod or bar, 25, whose upper end is adapted to engage with the under side of the damper and whose lower end is adapted to be engaged by some portion of the oven burner attachment; whereby, when the oven 95 burner attachment is placed in the oven, the rod or bar 25 is raised and the damper 23 is opened, while, upon removing the burner attachment, the rod or bar is allowed to drop and the damper to close. Thus the 100 damper will always be open when the burner is in place, and therefore the combustion gases and, in case the flame should be extinguished while the gas is still flowing, then the escaping gas, will always be carried up 105 the chimney and will not pass out into the room in which the range is located. On the other hand, whenever the burner is removed, the damper will automatically close so that none of the heat of the oven will be lost on 110 account of this opening when the coal fire is being employed.

The damper-operating rod or bar may be actuated in any suitable way from the burner attachment. In the arrangement 115 shown, I have connected to the rear end of the oven burner a finger, 26, so shaped that when the rod or bar 25 is down, the end of the finger may be inserted beneath it when the burner is placed in the oven with its 120 front end raised, and will thereafter lift the actuating rod or bar when the front end of the burner is lowered.

If desired, there may be placed in the top 125 of the oven a shallow auxiliary flue, 27, into which the combustion products must pass before they can reach the discharge outlet 22. In the arrangement shown, the flue 27 consists of a narrow flanged plate having its flanges resting against the under side of the 130

5 top wall of the stove, the plate having numerous perforations, 28, therethrough for permitting the passage of the combustion gases. The auxiliary flue extends along the center of the top of the oven just in front of the damper 23, and has a width somewhat greater than the length of the damper. In order not to decrease the height of the oven on account of the auxiliary flue, this member 10 may be made in the form of a drawer supported upon suitable ledges or rests, 29, projecting downwardly from the top wall of the oven. When the oven burner is put in place, the auxiliary flue may also be slipped 15 in position, the flue being removed when the burner is taken out and leaving the upper portion of the oven without any obstruction.

20 Projecting inwardly from the walls of the oven at some distance above the plane of the top of the flame spreader when the latter is in position in the stove, are rests or ledges, 30, upon which may be seated a plate, 31, preferably of such dimensions 25 that it will extend completely across the oven in both transverse directions. The plate, 31, is provided with openings, 32, extending through the same. When the plate 31 is in position the combustion gases flowing up around the flame spreader 17 must flow inwardly beneath the plate 31 until they reach the holes 32, thus permitting the heat from the burner to be concentrated between the flame spreader and the plate 31. 30 The plate 31 has downwardly-projecting members provided with inwardly-extending ledges, 33, upon which a broiling pan may be set. By using the plate 31, food may be broiled in the space between it and the flame spreader and thus make it unnecessary 35 to employ a separate broiling burner.

40 In the base of the range I place a long, narrow door, 35, through which the burner, the plate 31 and the flue 27 may be passed so as to house them in the base of the range 45 when they are not in use. For the purpose of supporting the attachments in the base of the range I place several transverse rods within the base, the rods being so disposed 50 that the attachments may be laid thereon. The rods are preferably supported loosely as, for example, in suitable seats, 37, so that they may be lifted out and cleaned when occasion requires.

55 While I have illustrated and described with particularity only a single preferred form of my invention, I do not desire to be limited to the exact structural details thus illustrated and described, but intend to 60 cover all forms and arrangements which come within the terms employed in the definitions of my invention constituting the appended claims.

I claim:

65 1. The combination with the oven of a

coal stove provided with a discharge outlet at the upper rear corner, a damper for said outlet, a perforated detachable flue adapted to be set in the upper portion of the oven in front of said damper, a burner 70 adapted to be detachably mounted in the oven, and means controlled by the burner for actuating said damper.

2. The combination with the oven of a coal stove, of an oven door hinged at its 75 lower end, a gas pipe arranged outside of the oven and terminating adjacent to said door, a burner adapted to be detachably set in the oven, said burner having an extension adapted to be engaged by the end of said 80 gas pipe, said door having a section removed at its hinged edge to provide an opening for the passage of said extension, and an auxiliary gravity door carried by the main door and adapted to close said opening when the 85 burner is removed.

3. The combination with the oven of a coal stove, of an oven door, a burner adapted to be detachably set in the oven, said burner having laterally and downwardly 90 projecting wings forming with the burners an inverted trough adapted to rest at its edges upon the bottom of the oven, said oven door having an opening adapted to register with the front end of said trough, 95 and a burner intake extending from said burner through said opening.

4. The combination with the oven of a coal stove, of an oven door, a burner adapted to be detachably set in the oven, said burner having laterally and downwardly 100 projecting wings forming with the burner an inverted trough adapted to rest at its edges upon the bottom of the oven, said oven door having an opening adapted to register with the front end of said trough, 105 a burner intake extending from said burner through said opening, and an auxiliary door mounted on the main door for closing said opening when the burner is removed from the oven.

5. The combination with the oven of a coal stove, of a burner adapted to be detachably set into the oven, said burner having a transverse deflector plate extending across 115 the top of the same, and a perforated plate detachably supported within the oven at a short distance above said deflector plate, said perforated plate having ledges on the under side for engaging with a pan to support the same.

6. The combination with the oven of a coal stove, of a burner adapted to be detachably set into the oven, a deflector plate arranged above the burner and having a width slightly less than the width of the oven, and a second plate detachably supported within the oven at a short distance above said deflector plate, and means on said second plate for suspending a pan. 125 130

7. The combination with the oven of a coal stove, of an oven door hinged at its lower end, a gas pipe arranged outside of the oven and terminating beneath and adjacent to the door, said door having an opening therethrough at its hinged edge adapted to register with the terminal of the gas pipe when the door is swung down, an auxiliary gravity door carried by the oven door and adapted to close said opening when the oven door is closed and to uncover the opening when the oven door is open, and a burner adapted to be detachably set in the oven and provided with an extension adapted to extend through said opening in the oven door and engage with the terminal of the gas pipe.

8. The combination with the oven of a coal stove, of a burner adapted to be detachably set in the oven, said burner having laterally and downwardly projecting wings forming with the burner an inverted trough adapted to rest at its edges on the bottom of the oven, the oven having an opening through one of its walls adapted to register with one end of said trough, and a burner in-

take extending from said burner through said opening.

9. The combination with the oven of a coal stove, of a burner adapted to be detachably set into the oven, said burner having laterally and downwardly projecting wings forming with the burner an inverted trough, a transverse deflector plate secured to the burner and lying at some distance above the same, and means for admitting gas to the burner and air to said inverted trough.

10. In a coal range, an oven, a removable gas burner attachment adapted to be placed in the oven, supporting rods lying horizontally below the bottom of the range for supporting said attachment when the latter is not in use, and a door in the front wall of the range in the plane of said supporting rods.

In testimony whereof, I sign this specification in the presence of two witnesses.

GEORGE W. CLARK.
